(57) **CLAIM**

I claim the ornamental design for a child's steerable riding toy with brakes and pivoting, spring-biased, hand-operated propelling device, as shown and described.

DESCRIPTION

FIG. 1 is a perspective view of a child's steerable riding toy with brakes and pivoting, spring-biased, hand-operated propelling device showing my new design;

FIG. 2 is a side elevational view thereof;

FIG. 3 is a top plan view thereof;

FIG. 4 is a front elevational view thereof;

FIG. 5 is a rear elevational view thereof; and,

FIG. 6 is a bottom plan view thereof.
